(57) **CLAIM**

The ornamental design for a hitch vise, as shown and described.

DESCRIPTION

FIG. 1 is a front perspective view of a hitch vise showing my new design.

FIG. 2 is a rear perspective view thereof.

FIG. 3 is a front elevational view thereof.

FIG. 4 is a first side elevational view thereof.

FIG. 5 is a rear elevational view thereof.

FIG. 6 is a second side elevational view thereof.

FIG. 7 is a top plan view thereof; and,

FIG. 8 is a bottom plan view thereof.

The portions illustrated in stippled/phantom lines in the drawings do not form part of the claimed design.
